(57) **CLAIM**

The ornamental design for an elbow for a rail system, as shown and described.

DESCRIPTION

FIG. 1 is a front perspective view of an elbow for a rail system;

FIG. 2 is a side view of the elbow of FIG. 1;

FIG. 3 is a front view of the elbow of FIG. 1;

FIG. 4 is a rear view of the elbow of FIG. 1;

FIG. 5 is a bottom view of the elbow of FIG. 1;

FIG. 6 is a top view of the elbow of FIG. 1; and,

FIG. 7 is an opposing side view of the elbow of FIG. 1.

In the drawings, the broken lines depict portions of the article that form no part of the claimed design.
